UNITED STATES PATENT OFFICE.

WALTER BABENDERERDE, OF CHICAGO, ILLINOIS, ASSIGNOR, BY MESNE ASSIGNMENTS, TO HARMONY SPRING CUSHION CO., A CORPORATION OF ILLINOIS.

SPRING-CUSHION CONSTRUCTION.

1,382,594.

Specification of Letters Patent. Patented June 21, 1921.

Application filed July 29, 1918. Serial No. 247,316.

To all whom it may concern:

Be it known that I, WALTER BABENDERDE, a citizen of the United States, and a resident of Chicago, in the county of Cook and State of Illinois, have invented certain new and useful Improvements in Spring-Cushion Constructions, of which the following is a specification.

My invention relates to a construction for spring cushions and the like, and has for its primary object the provision of an improved spring element by the use of which practically noiseless cushions may be constructed without necessitating the use of cloth pockets or other flexible separating elements between the coils of adjacent elements. Another object is the provision of a novel form of spring element adapted for grouping into larger spring units for providing within any given area the maximum cushioning effect and a low weight of material. A further object is the provision of an improved cushion construction which, in addition to the above mentioned advantages, is so arranged that, under compression, the coils of one spring element cannot interlap with those of adjacent elements and so shorten the compressible distance of the cushion by filling up the spaces between superposed coils of any pair of spring elements; this object being accomplished without the interposition of those flexible webs commonly employed for such purpose. A further object is the provision of a cushion construction simple in form and cheap to manufacture.

Other objects and advantages of the invention will appear from the following description, taken in conjunction with the accompanying drawings which form a part of this specification and illustrate the preferred embodiment of the invention.

In the drawings:

Figure 1 is a perspective view (with portions broken away and the padding turned up) of a spring cushion constructed in accordance with the present invention.

Fig. 2 is a fragmentary top plan view thereof with the padding and covering removed.

Fig. 3 is a fragmentary section on line 3-3 of Fig. 2.

Fig. 4 is a partial section on line 4-4 of Fig. 2, with the spacing wires removed, and

illustrating the oppositely inclined relation 55 between contiguous sides of the coils of adjacent spring elements.

Fig. 5 is a plan view of a modified form of unit constructed by a different grouping of the spring elements of the present invention.

Fig. 6 is a view in perspective of a modified form of spring element of this invention, showing the same constructed of round wire.

Reference numeral 10 indicates generally the spring unit of this invention, this unit comprising a prism-shaped helix of spring wire in the form of an isosceles triangle when viewed from either end. Each complete coil of the helix defines a triangle having two equal legs connected by a base; the bases of all the coils of one helix lying in a common plane, and the corresponding legs of each coil lying respectively in two planes 70 which preferably form a right angle with each other. While in the preferred embodiment of the invention an end view of the spring element defines an isosceles right triangle, it is to be understood that the principles of the present invention are applicable to constructions wherein the end view of the spring element defines a square or any other flat sided figure. Within each of the three planes defined by the base and 85 sides of the prism, the respective bases and legs of the coils of the helix lie parallel to each other and spaced apart in the plane, the opposite ends of each element being tapered as shown at 11, if it is desired to 90 cause the ends of the helix to define parallel planes at right angles to the axis of the helix. For convenience in description the base of each coil of the helix is numbered 12, the left hand leg 13, and the right hand 95 leg 14.

In constructing a cushion from the above described spring element, every element employed in the cushion comprises a helix wound in a common direction, preferably 100 clockwise or in the manner of a right threaded screw. For the purpose of securing a maximum cushioning effect within any given portion of the weight supporting of the cushion, as well as for facility in assembling, the construction which I prefer is that in which four elements are grouped together to form a unit, square in plan view

(as best seen in Fig. 2) and in which the sides of the square comprise the bases of the four helixes, the legs of the coils of each helix projecting toward the center of the square. Preferably the four elements of each unit are slightly spaced apart, and the various units are also preferably spaced the same distance from each other in the cushion, these spacings being secured through any suitable media, although I conceive the simplest to be the spacing wires 15 running from front to back of the cushion, and the identical spacing wires 16 crossing wires 15 at right angles. As best seen in Fig. 3, these wires traverse the cushion along its top and bottom and extend from a frame wire 17 which defines the top or bottom edge of the cushion, to the center of the adjacent base of the end coil of one helix, around which it is looped as at 18; thence directly across the coil to the apex thereof, where it is looped as at 19 about the coil; thence in the same direction to the apex of the corresponding coil in the opposite helix of the unit, about which it is looped as at 20; thence to the center of the base of the last mentioned coil, about which it is looped as at 21; thence similarly across each unit to the opposite side of frame wire 17. The ends of each spacing wire are secured as at 22 to opposite parallel reaches of the frame wire 17.

Because of the fact that the spring elements are helixes wound in a common direction, those legs, or bases of the coils of adjacent helixes which are positioned substantially at the same height in the cushion are oppositely inclined with respect to each other, so that, when viewed as in Fig. 4, they cross each other. Great importance attaches to this arrangement, inasmuch as the central coils of adjacent elements in the cushion, when under pressure, and therefore distorted against each other, cannot interfit but can only slide across each other. In Fig. 4 the legs 13 of the left hand element are shown in elevation, as viewed from the interior of the helix, and these legs 13 slant downwardly from left to right toward the center of the figure. In the space between the legs 13 of the left hand element the oppositely slanted legs 14 of the element beyond are seen in elevation, the remainder of these legs of the element beyond, being dotted behind the legs 13; in the right hand element of Fig. 4 the full elevation of the leg is shown while the adjacent legs 13 of the element just beyond appear back of legs 14 and show in full lines only in the spaces between the legs 14; in this right hand element the full line legs slant downwardly from left to right, and the legs 13 behind them slant downwardly from right to left.

In practice adjacent spring elements will be distorted under the pressure of a person

sitting upon the cushion, so that the central coils of adjacent elements will be brought into contact in many instances, but the binding wires 15 and 16 prevent relative horizontal movement of the upper and lower ends of the helixes. As seen in the drawings, the legs 13 of the coils of each helix are opposed to the legs 14 of the coils of an adjacent helix, while the bases of the coils of each helix, in the body of the cushion, are opposed to the bases of the coils of a helix in an adjacent unit. Not only are all of these opposed legs and bases slanted in opposite directions from each other with respect to the horizontal, so that they merely slide against each other without the possibility of the coils of one helix entering between the coils of another, but the bases of the coils of each helix are in a common plane, and all the legs 13 of each helix are in another common plane, and all the legs 14 of each helix are in a third common plane. By the arrangement of the present invention the binding wires 15 and 16 so maintain adjacent helixes that the opposed base planes of adjacent units are normally parallel to each other while the planes of opposed legs 13 and 14 are also normally parallel to each other. Because of this parallelism, and because of the further fact that each leg and each base of every coil remains straight under pressure even though slightly twisted, the action of the cushion, when a weight is placed upon it or removed from it, is practically noiseless. This is due to the fact that while the parallel planes defined by opposed bases, for example, may belly toward each other along the vertical lines until they touch and rub against each other, there is at the same time no appreciable distortion of these bases within the bellied planes. In other words, when the cushion is under compression, two opposed bases of adjacent coils, though in contact with and crossing each other, have their juxtaposed surfaces in a common plane; not only at the point where those surfaces actually touch in the crossing of the bases, but also through all the remaining juxtaposed or outer surfaces of both planes. It is thus seen that whether adjacent spring elements are constructed of flat or round wire, there can be no locking between contacting bases of adjacent elements or contacting legs of adjacent elements for the reason that the opposed bases or legs can only slide against each other and cannot catch one upon the other.

In the preferred form of construction a plurality of elements 10 are grouped into the square units above described, and a sufficient number of these units assembled to form a cushion or mattress of the size desired, all of the units being identical and of equal length. Frame wires 17 are posi-

tioned about the bottoms and tops of the assembled units, and the units secured in position within the frame wires and in equally spaced relation to each other by 5 means of the binding wires 15 and 16. One or more pads 23 are laid upon the tops of the elements 10 and the upper fame wire 17, and the whole cushion thus formed is enclosed by means of the ordinary cover 24 of 10 leather or other suitable material. The cover and padding may be tufted by means of buttons 25.

In Fig. 5 is illustrated a unit formed by 15 grouping eight of the spring elements of the present invention, instead of four; the elements themselves remaining the same as heretofore described. In this grouping the unit is square in end view, the sides of the squares being defined by the legs of the various coils and the diagonals of the squares being formed by the bases of the various coils. In Fig. 6 a spring element 10^a is 20 shown formed of wire round in cross-section instead of flattened; and it is to be noted that the advantages of this invention 25 are inherent in cushions formed of round-wire spring elements as well as in those formed of wire different in cross-sectional contour.

30 I claim:

1. A spring unit for cushions, comprising a plurality of prism shaped helixes grouped together to form in end contour a regular polygon.

35 2. A spring unit for cushions, comprising a plurality of identical prism-shaped helixes, each being in end contour an isosceles right triangle, and means engaging the ends only of said elements for retaining said ends 40 against relative transverse movement; said elements being grouped together to form a unit which in end contour is a regular polygon.

45 3. A spring unit for cushions, comprising a plurality of identical prism-shaped helixes, each being in end contour an isosceles right triangle, and means engaging the ends only of said elements for retaining said ends 50 against relative transverse movement, said elements being spaced from each other and

grouped to form in end contour a regular polygon.

4. The combination of four identical prism-shaped helixes of spring metal which in end view are isosceles right triangles, and 55 means for retaining said helixes together in a unit wherein the bases of the four prisms form the side faces of a square prism and the apex edges of said prisms are positioned centrally of said prism shaped unit. 60

5. The combination of four identical prism-shaped helixes of spring metal which in end view are isosceles right triangles, and 65 means for retaining said helixes together in a unit wherein the bases of the four prisms form the side faces of a square prism and the apex edges of said prisms are positioned centrally of said prism-shaped unit, said means maintaining the four elements uniformly spaced apart. 70

6. In a cushion construction, the combination of a plurality of identical prism-shaped helixes of spring metal having their axes parallel, said helixes being each a regular polygon in end view, and means whereby 75 the helixes are grouped together in regularly shaped units.

7. The combination with frame wires, of a plurality of identical prism-shaped elements of spring wire having their axes parallel and grouped closely together in regularly-shaped units, and spacing means for 80 securing said units in close association within the frame wires.

8. A spring cushion construction, comprising in combination a plurality of spring units each formed of four identical prism-shaped helixes of spring wire which in end elevation are isosceles right triangles, the right angles of the triangles being grouped 85 together at the center of each unit, and the bases of the four triangles forming the sides of a square, the sides of adjacent helixes in each unit being parallel to each other and the sides of adjacent units being parallel to 90 each other. 95

In witness whereof I have hereto affixed my signature.

WALTER BABENDERERDE.
